UNITED STATES PATENT OFFICE.

CARL J. ERIKSON, OF ROCKFORD, ILLINOIS.

TRAP.

SPECIFICATION forming part of Letters Patent No. 365,058, dated June 21, 1887.

Application filed February 7, 1887. Serial No. 226,821. (No model.)

To all whom it may concern:

Be it known that I, CARL J. ERIKSON, a citizen of the United States, residing at Rockford, in the county of Winnebago and State of Illinois, have invented certain new and useful Improvements in Traps for Capturing Rats, Mice, &c., of which the following is a specification.

The object of my invention is to produce, at minimum cost, a simply-constructed trap for capturing small animals, that may be quickly and easily set.

My invention relates to that class of traps commonly known as "self-setting" or "self-locking" traps; and it consists in constructions and combinations hereinafter described and claimed.

Referring to the accompanying drawings, which form a part of this specification, Figure 1 is a view of a side elevation of my improved trap set ready for use. Fig. 2 is a view of a side elevation of the same sprung. Fig. 3 is a plan view of Fig. 2.

Like letters of reference indicate corresponding parts throughout the several views.

25 A represents the lower jaw of the trap.

A' A² represent perpendicular standards secured to the jaw A. The standard A' is broken away in Figs. 1 and 2, to better show the interior construction of the trap.

30 B represents the spring of the trap, formed, preferably, of a single piece of strong wire, and secured to the jaw A by inserting the ends B' thereof through the openings A³ in said jaw A.

C represents the upper jaw of the trap, secured to the spring B by means of the loops C', the ends C² of which are inserted through said jaw C and clinched against the under side thereof, as indicated by the dotted lines C³.

C⁴ represents an ear for raising the jaw C.

40 D represents a horizontal rock-shaft the ends whereof are inserted through tubular openings in the standards A' A², which openings serve as bearings for said rock-shaft D.

E represents a trigger consisting of a substantially horizontal arm, E', a downwardly-projecting arm, E², lying at right angles therewith and provided with the rectangular bends E³ E⁴, and a tubular portion, E⁵, connecting said arms together, both of said arms lying at right angles with the rock-shaft D and being mounted thereon.

F represents a horizontal rock-shaft mounted by inserting the ends thereof into circular bearings in the standards A' A².

G represents a trap-pan mounted upon the 55 rock-shaft F and provided with the weight G', the latter being formed, preferably, integrally with the trap-pan G and being heavier than the same, in order that the weight thereto may tilt the trap-pan G upward whenever both the 60 weight and trap-pan are free to move.

G² represents a lug projecting from the upper side of the trap-pan G', the function whereof is to engage with the free end of the trigger-arm E², and thereby lock the trap set. 65

H represents a bait-box composed, respectively, of the plane vertical side H', the curved vertical side H², and the cover H³, hinged upon the side H', which is provided with openings H⁴, for the purpose of exposing to view any 70 bait that may be placed in said box.

To set the trap, I press with one hand upon the upper ends of the standards A' A², and with the other hand I grasp the ear C⁴ and raise the jaw C to the position shown in Fig. 1. As the 75 jaw C moves upward, it comes in contact with the trigger arm E² and carries that upward also. At the same time the trap-pan G is tilted upward by the weight G', and the free end of the trigger-arm E² travels forward until it so passes the highest point of the lug G² and engages therewith, thereby locking the trap set.

I claim—

In a self-setting trap, the combination, with the lower jaw, of an upper jaw hinged to said lower jaw by means of the spring B, which actuates said upper jaw, the trigger consisting of a substantially horizontal arm, a downwardly-projecting arm provided with rectangular bends E³ E⁴, and a tubular portion, 90 E⁵, connecting said arms together, the rock-shaft whereon said arms are mounted, a trap-pan provided with an upwardly-projecting lug and weight, G', and a rock-shaft, whereon said trap-pan and weight are mounted, substantially as described, and for the purpose set forth.

CARL J. ERIKSON.
